UNITED STATES PATENT OFFICE

2,161,915

CAR CONSTRUCTION

Otho C. Duryea, Waterbury, Conn., assignor to
 O. C. Duryea Corporation, Wilmington, Del., a
 corporation of Delaware

Application November 22, 1937, Serial No. 175,924

7 Claims. (Cl. 105—226)

This invention relates to railway car bolsters and more particularly to the construction of the bolster in a railway car equipped with the Duryea underframe, although not restricted to this particular use.

The Duryea underframe, as described for example in United States Patent No. 1,693,194, issued November 27, 1928, to Otho C. Duryea, embodies a draft and buffering column that is movable longitudinally relative to the car body in response to draft and buffering forces to which the car couplers are subjected, suitable cushioning mechanism being interposed between the draft and buffering column and the car body. Hence the transversely extending body bolsters adjacent the ends of the car are each provided with openings through which this column extends. In the usual construction the column is formed by spaced channels extending through corresponding spaced openings, the central portion of the bolster which is embraced by the channels being constituted by a strong rigid center brace. It has been proposed to form the laterally extending parts of the bolster together with the center brace in a single casting, as shown in the aforesaid Duryea patent, but this construction, while practicable, requires a large, heavy casting that is difficult to make and heavy and cumbersome to handle. Another construction which has been extensively and successfully used comprises a center brace casting of the general type shown in United States Patent No. 1,938,744, issued December 12, 1933, to Otho C. Duryea, together with riveted laterally extending bolster construction including top and bottom bolster cover plates and a vertical diaphragm or diaphragms extending between said cover plates. This construction involves some duplication of material due to juxtaposed riveted surfaces, but particularly it involves a large number of riveting operations as well as the possibility that the rivets may rust in service or work loose unless carefully driven.

The present invention relates to a bolster of novel construction which avoids the foregoing disadvantages and is strong and rigid in service while at the same time economical to manufacture, and which facilitates welding and reduces the length of the necessary weld lines, although certain advantages of the invention can also be realized in riveted bolsters. More particularly, the present invention relates to a novel construction and assembly of the bolster bottom cover plate and diaphragms with associated bolster construction which usually comprises the center brace casting and top cover plate, the center plate

and the torque arms. For purposes of illustration, such associated bolster construction as shown hereinafter embodies in part the structure shown in my prior application Serial No. 164,050, filed September 15, 1937, for Car construction, but it will be understood that the invention may, if desired, be embodied in any other suitable bolster construction.

One embodiment of the invention has been illustrated in the accompanying drawings but it is to be expressly understood that said drawings are for purposes of illustration only and are not to be taken as a definition of the limits of the invention, reference being had to the appended claims for this purpose.

In the drawings:

Fig. 1 is an elevation in section of bolster construction embodying the invention;

Fig. 2 is a horizontal section on the line 2—2 of Fig. 1;

Fig. 3 is a vertical section taken along the line 3—3 of Fig. 1;

Fig. 4 is a perspective view of combined bottom cover plate and diaphragm construction; and

Figs. 5, 6 and 7 are details illustrating welded connections employed in the structure shown in Figs. 1, 2 and 3.

As shown in my aforesaid application, the bolster construction is designed for use with a Duryea underframe of the type disclosed in the aforementioned patents and is accordingly provided with spaced openings 1, 1 through which extend the usual channels forming the draft and buffering column as above described. This column together with the cushioning mechanism and its connections to the column and car body constitute no part of the present invention and in the interest of simplicity are not shown herein, but it will be understood that any suitable long travel column and cushioning devices can be employed, such as those disclosed for example in the two Duryea patents referred to above.

As further shown in my aforesaid application, the center brace casting 2 is disposed between the openings 1, 1 and is generally T-shaped, said casting comprising a lower portion intermediate and separating the openings 1, 1 and an upper head which extends laterally above the openings. This head comprises a lower substantially horizontal wall 4 and vertical webs 5 extending transversely of the car body and supporting a top cover plate 6 which is suitably welded thereto. The cover plate 6 extends between and is suitably secured at its ends to a reinforcing member 7 which in turn may be secured to the side sills 55

of the car in any suitable manner. Additional vertical webs 8 extend longitudinally of the car body on the wall 4 and to the outer webs 8 are welded the longitudinally extending torque arms 9. This welded connection is illustrated in detail in Fig. 7 wherein the upper flange 10 of the torque arm extends horizontally under the cover plate 6 and the web 8 is welded to the torque arm at 11. The torque arms 9, as shown in Fig. 3, extend from the end sill 12 of the car body inwardly to the bolster and may terminate at any desired point inwardly of the bolster, being herein extended to the cross bearer 13. The upper flanges 10 of the torque arms may be welded to the edges of the cover plate 6 as shown at 14.

The structure thus far described, which is substantially as disclosed in my aforesaid prior application, is associated herein with novel means for forming the bolster bottom cover plate and diaphragms and for assembling the same. These means comprise a structure substantially U-shaped in cross section, the lower portion of which constitutes a bottom cover plate and the sides of which form a pair of spaced substantially vertical diaphragms extending between the cover plates. The integral bottom and side walls of this structure may be formed in any suitable manner. In the form shown, the bottom cover plate and diaphragms are formed from a plate 30 (Fig. 4) having a central or bottom portion 15 which is preferably thicker than the two side portions 16, the latter being bent upwardly along the parallel lines 17 as shown in dotted lines in Fig. 4, whereby the central portion 15 and the side portions 16 are adapted to form respectively the bottom cover plate and the spaced parallel diaphragms of the bolster as shown in cross section in Fig. 3. The outer edges of the side portions 16 may have any suitable shape depending 40 on the configuration of the bolster. In the present construction, as shown in Fig. 1, the bolster tapers upwardly toward the side sills of the car and accordingly the side portions 16 of the plate shown in Fig. 4 are tapered so that the plate becomes narrower toward one end. When the side 45 portions are bent upwardly for assembly in the bolster, the central or bottom portion 15 may therefore be disposed at an angle to the horizontal, as shown in Fig. 1 while the top edges of the side or diaphragm portions 16 are substantially horizontal and conform to the top cover plate 6 as shown in Fig. 1.

The upper edges of the diaphragm portions 16 are preferably secured to the top cover plate 6 by welding as indicated at 18 (Fig. 3) throughout substantially the entire transverse extent of the bolster. To accommodate the upper flanges 10 of the torque arms, the corners of the diaphragm plates 16 may be notched as indicated at 19 in Figs. 1 and 4. The inner vertical edges of the diaphragm portions 16 are disposed against the webs of the torque arms 9 and are preferably secured thereto by welding at 20 as shown in Fig. 2. The ends of the diaphragm portions 16 engage 55 the webs of the reenforcing members 7 and are preferably secured thereto by welding at 22 as shown in Fig. 2. Fig. 6 is a detail of a welded connection which illustrates the welds 18, 20 and 22.

70 It will be seen that these elements form hollow bolster construction of U-shaped substantially rectangular cross section extending transversely on each side of the center brace 1, which construction is completed by integrally connecting 75 the inner edges of the central or bottom portions

15 beneath the center brace. Preferably these elements are made separately as shown and the connection between them is constituted by the center plate 23 which preferably is secured to the center brace by welding and as shown in Fig. 1 comprises laterally extending flanges 24 corresponding to and terminating adjacent the inner edges of the plates 15 and being connected thereto by welding. Preferably also the same weld line is employed to form a connection between the bottom cover plate and the vertical torque arms 9. To this end the lower flanges 25 of the torque arms 9 are cut away where they pass through the bolster and the parts are disposed so that the adjacent edges of the flanges 24 and the plates 15 and the lower edges of the webs of the torque arms 9 all meet substantially along a common line through the bolster. As shown in detail in Fig. 5, the edges of the plates 15 and the flanges 24 may be spaced apart by a distance sufficient to permit the entry therebetween of the lower edge of the torque arm 9, and for convenience in welding the adjacent edges of the plates 15 and flanges 24 may be tapered so that the assembly of these three elements forms a substantially V-shaped groove, the bottom of which is constituted by the edge of the torque arm 9 and the sides of which are formed by the tapered edges of the plates 15 and flanges 24. This groove is preferably substantially filled with weld metal as shown 30 in Fig. 5 so as to secure a strong and rigid connection between the three meeting elements.

Side bearing members 26 may be secured to the bottom cover plate 15 in any suitable manner as by rivets 21, and to provide greater stiffness and rigidity, vertical plates 28 may be welded along their bottom edges to the bottom plates 15 as indicated at 29 and at their ends to the diaphragms 16 as indicated at 30.

It will be seen that this construction provides 40 a built-up bolster which is welded into an integral rigid unit whereby riveting operations are substantially eliminated. The construction embodies a minimum of parts and is so designed as to provide weld lines at points and in directions 45 best adapted to withstand the forces to which the bolster is subjected in service. A minimum of material is employed while at the same time the extent of the welding operations required is kept at a minimum, particularly owing to the integral 50 construction of the bottom cover plate and diaphragms and to the arrangement permitting a single weld for uniting three meeting elements.

While only one embodiment of the invention has been described and illustrated in the drawings, it will be understood that the invention is not limited to this embodiment but is capable of a variety of mechanical expressions and that changes may be made in the form, details of construction and arrangement of parts without departing from the spirit of the invention. Reference is therefore to be had to the appended claims for a definition of the limits of the invention.

What is claimed is:

1. Railway car bolster construction comprising 65 a center structure including a center brace and a center plate and having an intermediate portion of reduced width to provide openings for passage of movable elements through the bolster, a top cover plate welded to said center structure and 70 extending laterally on each side thereof, and bottom cover plate and diaphragm structure comprising U-shaped elements substantially abutting and welded to said center structure and extending laterally one on each side thereof, the bot- 75

toms of said U-shaped elements forming parts of the bottom cover plate and the sides abutting and being welded to said top cover plate to form substantially vertical diaphragms.

ments abutting and being welded to said vertical plates and their upper edges abutting and being welded to said top cover plate to form vertical diaphragms, the abutting edges of said bottoms and flanges and the lower edges of said vertical plates meeting substantially in a common line and being united by a common weld. 5

5. Railway car bolster construction comprising a center brace having a portion of reduced width to provide openings for the passage of movable elements, a top cover plate secured to said center brace and extending laterally on each side thereof, a center plate secured to the bottom of said center brace and having flanges extending laterally on each side thereof, U-shaped elements one on each side of said center brace, the inner edges of the bottom thereof being adjacent to the outer edges of said flanges, vertical plates extending longitudinally of the car body through said bolster, said vertical plates forming the outer sides of said openings and having their lower edges interposed between the adjacent edges of said bottoms and flanges to form therewith a common welding groove substantially filled with weld metal, the vertical sides of said U-shaped elements forming diaphragms and having their upper edges welded to said top cover plate and their inner edges welded to said vertical plates. 10 15 20 25

6. In a railway car bolster having center brace and center plate structure and a top cover plate extending transversely thereof on each side, the combination of a pair of elements substantially U-shaped in cross section, the bottoms thereof forming bottom cover plates and the sides thereof being welded to said top cover plate, and vertical plates extending longitudinally of the car through said bolster, said structure having laterally extending flanges the outer edges of which substantially meet the inner edges of said bottoms and the lower edges of said vertical plates, and common welded connections between said meeting edges. 30 35 40

7. In a railway car bolster having center brace and center plate structure and a top cover plate extending transversely thereof on each side, the combination of a pair of elements substantially U-shaped in cross section, the bottoms thereof forming bottom cover plates and the sides thereof being welded to said top cover plate, and vertical plates passing longitudinally through said bolster, said structure having laterally extending flanges the outer edges of which are disposed adjacent the inner edges of said bottoms with the lower edges of said vertical plates partially interposed between them to form a groove filled with weld material. 50 55 45

OTHO C. DURYEA.
